UNITED STATES PATENT OFFICE.

ALBERT BELZ, OF UNTER-GOLDACH, SWITZERLAND.

SPOOLING-MACHINE.

1,141,604.

Specification of Letters Patent.

Patented June 1, 1915.

Application filed June 9, 1914. Serial No. 844,013.

To all whom it may concern:

Be it known that I, ALBERT BELZ, a citizen of the Republic of Switzerland, residing at Unter-Goldach, Klosterstrasse, 5 Switzerland, have invented new and useful Improvements in Spooling-Machines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to spooling-machines and particularly to a device for securing the free thread end of the bobbins used in shuttle embroidering-machines.

In the hitherto proposed spooling-machines for winding up bobbins to be used in shuttle embroidering-machines the devices serving for securing the free thread end are usually brought to act upon the bobbin as soon as a second bobbin to be produced 25 has a predeterminate size. Now, it may occur that the spool mounted on the front end of the bobbin-shaft and whose thread end has to be secured is shifted in an axial direction. Such a shifting of the bobbin 30 takes place, for instance, when the tension of the thread to be wound on the bobbin is not great enough, or when the shape of the bobbin is somewhat conical. The yarn is be wound up may also contain too much 35 moisture, so that the bobbin cannot be so easily shifted on the bobbin-shaft. This causes frequently a stemming of said bobbin, so that a kind of collar is formed behind the central winding wound on the bobbin. 40 These drawbacks are very much felt in spooling-machines, since the member for securing the free thread end may act beside the central winding when a shifting of the bobbin has taken place, so that said 45 member does not work in the proper manner or does not act at all. If, on the other hand, the bobbin has been stemmed, the securing member may only come in contact with said collar formed behind the central 50 winding of the bobbin and not with the central winding. In both instances the free thread end is either secured in an imperfect manner or it is not secured at all.

The object of this invention is to provide 55 in a device for securing the free thread end for spooling-machines a member for secur-

ing said end, which guides the last outer windings of the thread wound around the central part of the bobbin underneath the central windings previously wound around 60 said bobbin part.

One mode of carrying the invention into effect is shown by way of example in the accompanying drawings, in which:

Figure 1 is a side-view of the spooling-machine, Fig. 2 is an end view of the machine seen from the left hand side of Fig. 1, Fig. 3 is a corresponding view seen from the right hand side of Fig. 1 and Figs. 4-7 show details on different scales.

In the construction according to this invention as shown in the drawings 1 denotes the driving shaft of a spooling-machine. The friction disks 2 transmit the motion of this shaft to the bobbin-shaft 5 mounted in 75 the standard 4, which is adjustably mounted on the shafts 3. The standard 4 carries a roller 6 and it is acted upon by a spring 2^a, which presses said disks 2 one against another.

70 7 denotes a clutch member having a cam-disk shaped part. This member is fixed to a shaft 8 consisting of two halves touching one another at 11. One half of the shaft 8 is operatively connected by means of worm-gearing 9 to the shaft 1. A second clutch member 1 is capable of being adjusted in the longitudinal direction of said shaft 8, but is prevented from rotating relatively to this shaft. A helical spring 12 acting 85 upon the member 10 has a tendency to throw the members 7 and 10 in gear to couple the two halves of the shaft 8. A roller 14 of a lever 16 pivotally mounted on the base-plate 15 of the spooling-machine works 90 in an annular groove 13 of the clutch member 10. To the lever 16 there is pivotally connected a rod 17. This rod 17 may abut against a lever 18, in which case the clutch-member 10 is thrown out of gear, the spring 100 12 being then compressed. A support 19 of the standard 4 carries a frame 21, rotatably mounted on a shaft 20. In this frame 21 there is mounted a revolving drum 23 having a slot 22 and acting as a thread-guide. A tension spring 40 has a tendency to continually press said drum against the bobbin shaft 5. A toothed wheel-gearing 24 transmits the drive from the bobbin-shaft 5 to the drum 23. Within the drum 23 there 105 is provided a roller 25, mounted in a stationary manner in the frame 21. The lat-

110

ter has also a downward projecting arm 26 carrying at its lower end a pawl 27, which may engage the arm 18 to keep it in the position, in which the rod 17 lies behind the lever 18 (Fig. 2). The arm 26 carries a bracket 28 (Fig. 4) to which there is fixed the plate 29 provided with a slot and acting as an auxiliary thread guide. A sleeve 30 is rotatably mounted on the bracket 28 and 10 carries the member for securing the free thread end. This member consists of a wire 31 bent in the shape of a ring and having pointed ends.

32 denotes a spring, which has a tendency 15 to move the sleeve 30 in the direction of the arrow 33 shown in Fig. 4. This movement of the sleeve 30 is, however, limited by a stop (not shown in the drawings) of the bracket 28. 34, 35 is a double-arm lever. 20 The arm 35 of this lever carrying a roller 37 is pressed by means of the tension spring 36 acting upon the arm 34 against a disk 38 fixed to that half of the shaft 8 which carries the clutch member 7. The disk 38 25 has a cam-shaped surface 39. The arm 26 projects into the path of movement of the arm 34.

While the bobbin is wound up the drum 23 is in contact with the bobbin and the 30 part of the shaft 8 carrying the disk 38 remains stationary, the rod 17 abutting against the lever 18 and the roller 37 engaging the cam-shaped part 39 of the disk 38. The pawl 27 engaging the lever 18 35 keeps the latter in the proper position, while the auxiliary thread guide 29 and the wire 31 do not touch the thread, which has to be wound on the bobbin. After the bobbin to be produced has a certain diameter, the 40 drum 23 has been moved so far away from the bobbin-shaft 5, that the pawl 27 releases the lever 18, so that the latter acted upon by a spring 41 will be rotated and release the rod 17. The spring 12 throws 45 hereupon the clutch members 10 and 7 into gear. This causes a rotation of the disk 38 and the roller 37 glides off the projection 39, the lever 34, 35 being then rotated. Thereby the arm 34 moves the arm 26 in 50 such a manner, that the drum 23 is brought out of contact with the bobbin, while the auxiliary thread-guide 29 is moved into the path of movement of the thread. The latter passes now through the slot of the thread 55 guide 29, the central windings being thereby wound on the bobbin, while the ends of the wire 31 rest on the bobbin. The conical ends of the wire 31 guide the thread to be wound on the central part of the bobbin in 60 such a way toward their points, that the outer central windings of the thread come to lie underneath the windings wound previously on said part of the bobbin, so that after the bobbin-shaft 5 has been brought 65 to a standstill the last winding of the thread

will lie underneath the other windings wound on the central part of the bobbin. Thus the end of the thread is entangled and secured. When the roller 6 engages the cam-disk shaped part of the clutch-member 7 the bobbin-shaft 5 is brought to a standstill, the support 4 being then displaced in an axial direction and the friction wheel 2 mounted on the bobbin shaft 5 being moved away from the friction wheel 2 mounted on the shaft 1, so that the transmission of the drive is interrupted. When the wire 31 is returned in its position of rest, or when it is moved away from the bobbin, the wire can move in a lateral direction owing to its 80 shape and resiliency, so that it may be moved past the central windings without the latter being damaged. After a bobbin has been finished and the hereinbefore described members have been brought back 85 into their first position, the operator may start with the winding up of a new bobbin.

The described device has the advantage, compared with the devices mentioned at the beginning, that the member effecting the 90 securing of the thread end acts always at the right places.

What I do claim as my invention is:

1. In a device for securing the free thread end of bobbins for spooling machines, means 95 to form a central winding of the thread around the main winding, and a member brought into operation at the beginning of the central winding to conduct a portion of the thread being wound under the previously wound portion of the central winding.

2. In a device for securing the free thread end of bobbins for spooling machines, means to wind the thread around the central portion of the main winding, and a resilient 105 ring shaped member brought into contact with the bobbin after the main winding thereof is completed, said member having conical ends to conduct a portion of the thread being wound under the previously 110 wound portion of the central winding.

3. In a device for securing the free thread end of bobbins for spooling-machines, a movable bracket, an auxiliary thread-guide carried by said bracket, a ring-shaped wire 115 having resilient and conical ends resting on the bobbin and lying between the bobbin and the central windings wound on the bobbin, said ring being capable of rotating in the bracket, means for throwing said wire 120 and auxiliary thread-guide out of operation while the bobbin is wound up and means for moving said thread-guide into the path of movement of the thread after the winding up of the bobbin.

4. In a device for securing the free thread end of bobbins for spooling-machines, a pivotally mounted frame, a slotted drum acting as a thread-guide and supported by 125 said frame, a movable bracket carried by 130

an arm of said frame, an auxiliary thread-guide carried by said bracket, a ring-shaped wire having resilient and conical ends resting on the bobbin and lying between the 5 bobbin and the central windings to be wound on the bobbin, said ring being capable of rotating in the bracket and means for swinging said arm of the frame to bring said auxiliary thread-guide and said wire 10 into the operative position.

5. In a device for securing the free thread end of bobbins for spooling-machines, a main driving shaft, a bobbin-shaft, means for transmitting the drive from the main 15 shaft to the bobbin-shaft, an auxiliary shaft, means for transmitting the drive from the main shaft to the auxiliary shaft, a cam shaped disk fixed to said auxiliary shaft, a double-arm lever pivotally mounted on the 20 machine-frame, one of said lever-arms working together with said disk, a pivotally mounted frame, a slotted drum acting as a

thread-guide and supported by said frame, a movable bracket, an arm on said frame carrying the bracket and working together 25 with the other arm of said lever, an auxiliary thread-guide carried by said bracket, a ring-shaped wire having resilient and conical ends resting on the bobbin and lying between the bobbin and the central windings to be wound on the bobbin, said ring being capable of rotating in the bracket and means for pivoting said lever as soon as the auxiliary shaft is rotated to bring the auxiliary thread-guide and said wire into their 30 35 operative position.

In testimony that I claim the foregoing as my invention, I have signed my name in presence of two subscribing witnesses.

ALBERT BELZ.
